US0D1035421S

(12) **United States Design Patent** (10) **Patent No.:** **US D1,035,421 S**
(45) **Date of Patent:** **** Jul. 16, 2024**

(54) **ROPE CAPTURE DEVICE**

(71) Applicant: **Jameson, LLC**, Clover, SC (US)

(72) Inventors: **Benjamin Erwin**, Rock Hill, SC (US);
Blake Tomlinson, Statesville, NC (US)

(73) Assignee: **Jameson, LLC**, Clover, SC (US)

(**) Term: **15 Years**

(21) Appl. No.: **35/518,907**

(22) Filed: **Oct. 13, 2023**

(80) **Hague Agreement Data**

Int. Filing Date: **Oct. 13, 2023**

Int. Reg. No.: **DM/232689**

Int. Reg. Date: **Oct. 13, 2023**

Int. Reg. Pub. Date: **Nov. 3, 2023**

(51) **LOC (14) Cl.** **09-06**

(52) **U.S. Cl.**

USPC **D8/356**

(58) **Field of Classification Search**

USPC D8/349, 356, 72, 396

CPC F16G 11/14; F16B 39/28

(57) **CLAIM**

The ornamental design for rope capture device, as shown and described.

DESCRIPTION

1. Rope capture device

1.1 : Perspective

1.2 : Perspective

1.3 : Left

1.4 : Right

1.5 : Top

1.6 : Bottom

1.7 : Front

1.8 : Back
